[57] **CLAIM**

The ornamental design for a handle of a body cleaning brush, as shown and described.

DESCRIPTION

FIG. 1 is a front elevation of a handle of a body cleaning brush showing my design;

FIG. 2 is a rear elevation thereof;

FIG. 3 is a left side elevation thereof;

FIG. 4 is a right side elevation thereof;

FIG. 5 is a top plan view thereof;

FIG. 6 is a bottom plan view thereof;

FIG. 7 is a perspective view thereof;

FIG. 8 is a perspective showing the use of the handle according to my design; and,

FIG. 9 is another perspective also showing the use of the handle according to my design.

The broken lines shown in FIGS. 8 and 9 are for illustrative purposes only and form no part of the claimed design.
